CYLINDRICAL BRUSH

John E. Grogan, West Hartford, Conn., assignor to The Fuller Brush Company, Hartford, Conn., a corporation of Connecticut

Application July 30, 1954, Serial No. 446,789

8 Claims. (Cl. 15—182)

This invention relates to brushes and, more specifically, to an improved brush element or strip and to brushes formed therewith.

A brush strip ordinarily includes an elongated metal channel member of generally U-shaped cross section wherein the side walls of the channel member converge to engage and press against and thereby retain the central portions of brush fibers which are also included in the strip. The said central portions of the fibers are usually folded within the channel member around a core wire so that the end portions of the fibers project through the open face or longitudinally extending neck defined between the converging side walls. The core wire is generally located at least partly within the channel and extends longitudinally thereof to cooperate with the side walls of the channel member to retain the fibers.

In accordance with the conventional practice of brush manufacture utilizing brush strips, the said strips are mounted and secured to brush support structure. In a cylindrical or rotary brush, the support structure is generally cylindrical and ordinarily referred to as the "core" and may or may not be provided with a longitudinally extending opening. It is an ordinary practice to form a cylindrical brush by spirally winding or coiling a brush strip around the core.

Various means have been employed to mount and secure the metal channel member on the core. In some instances, the core has been provided with undercut grooves shaped to receive and retain the metal channel members which are inserted lengthwise within the grooves. In other instances, the converging side walls of the channel members have been engaged by relatively movable clamping devices and in still other instances, the side walls of the channel members have been provided with lateral extensions engageable by or within clamping devices or fastening members.

The general object of the invention is to provide a channel type brush element or strip which requires no fastening devices to hold the strip in a desired position in a cylindrical brush structure and which, in fact, requires no support structure or core in forming a cylindrical brush. As will be shown in detail hereinafter, this object is attained by providing flanges on the side walls of the metal channel members which are adapted to engage and be rigidly secured to similar flanges on the side walls of the channel member of an adjacent brush strip or the adjacent section or coil of the same brush strip.

Another object of the invention is to provide a brush strip which can be used in a variety of ways in brush manufacture and in the fabrication of cylindrical brushes at reduced cost without sacrificing strength in the brushes formed.

Other objects of the invention will be apparent from the drawing and from the following specification and claims.

In the drawing, I have shown in detail an improved brush strip and a brush embodiment illustrative of its use, but it will be understood that various changes may

2

be made from the construction shown and that the drawing is not to be construed as defining or limiting the scope of the invention, the claims forming a part of this specification being relied upon for that purpose.

5 Of the drawing,

Fig. 1 is a fragmentary perspective view of my improved strip;

Fig. 2 is a side view of a cylindrical brush constructed in accordance with the present invention and showing 10 a portion of the brush in longitudinal section to illustrate details; and

Fig. 3 is a view of the left-hand end of the brush shown in Fig. 2.

As shown in Fig. 1, my novel brush strip 10 includes an elongated metal channel member indicated generally by the reference numeral 12. The said channel member is transversely shaped throughout its length to define a generally U-shaped channel within a rear wall 14 and two integrally formed forwardly converging side walls 16 and 18. The channel member 12 is further transversely shaped throughout its length to provide a laterally extending flange 20 along the forward edge of the side wall 16 and a substantially coplanar laterally extending flange 22 along the forward edge of the side wall 18. One 25 of the flanges, for example the flange 20, is provided with a rearwardly offset marginal portion 24 which extends throughout the length of the channel member 12 and which terminates in one longitudinal edge 26. The other laterally extending flange, for example the flange 22, is provided with a forwardly offset marginal portion 28 which extends for the length of the channel member 12 and defines a longitudinal edge 30 thereon.

It is important to observe that the marginal portion or wing 24 is rearwardly offset from the flange 20 substantially the same distance that the marginal portion of the wing 28 is forwardly offset from the flange 22 and that the amount of offset in each case is no greater than the thickness of the metal stock used in forming the channel member 12. It will be quite apparent, the lateral flanges 20 and 22 being substantially co-planar, that when two channel members are joined in side-by-side relationship with the forwardly offset wing 28 of one channel member overlapping the rearwardly offset wing 24 of the adjacent channel member, the rear walls 14 of the channel members will reside in the same plane.

A layer of brush fibers 32 is also included in the structure of the brush strip and the fibers 32 may comprise any of the suitable metal, vegetable, animal or synthetic brush fibers commonly used. The said layer of fibers 32 is arranged so that the end portions of the fibers project generally forwardly through the channel neck defined between the converging side walls 16 and 18. Ordinarily, there is included a longitudinally extending wire core 34 which is at least partly within the channel member 12. A round wire is shown which is entirely within the channel. When the core wire is provided, the fibers are folded around the said wire within the channel member so that the forwardly projecting end portions of the fibers project either in two rows or in one row to provide the brushing surface. During manufacture, the layer of fibers 32, while straight, is deposited with the core wire 34 on the channel strip 12 before the side walls 16 and 18 are closed to their final positions. The core wire 34 is guided into the channel member, thus folding the central portions of the fibers in the layer 32 around it. The side walls 16 and 18 are then rolled or pressed against the central portions of the fibers to bind the several parts together by pressure.

It is a feature of the present invention that a cylindrical brush can be formed with the aforescribed brush strip 10. Such a cylindrical brush will comprise a plurality of similar brush strip convolutions having a common center

line and wherein the brush strip of each convolution comprises a channel member having an inner wall and two side walls defining a generally U-shaped channel and also having two oppositely and generally laterally projecting flanges, and wherein the brush strip of each convolution also comprises a layer of brush fibers secured within the channel and projecting outwardly therefrom, the flange at one side of each brush strip convolution engaging and being secured to the flange at the opposite side of the next adjacent brush strip convolution. Such a cylindrical brush is shown in Figs. 2 and 3 and indicated by the reference character C. The brush C is formed of a plurality of similar brush strip convolutions wherein the strip of each convolution comprises the channel member 12 having the rear wall 14, the side walls 16 and 18, the flanges 20 and 22 and the rearwardly and forwardly offset wings 24 and 28. The forwardly offset wing 28 of the strip in one convolution overlaps or embraces the rearwardly offset wing 24 of the strip in the next adjacent convolution. The overlapped wings 28 and 24 are secured to each other by welding in circumaxially spaced locations or by seam welding along the said wings. Thus, with the convolutions of the channel member rigidly connected together, the inner wall in one convolution is spaced from the center line the same distance as the rear wall in every other convolution.

It will be quite apparent that in forming a cylindrical brush C by engaging and welding together the channel members of adjacent convolutions of a brush strip, the said brush strip becomes self-supporting in the cylindrical brush. That is, a rigid connection is effected between the convolutions of the strip so that the channel member need not be mounted upon a separate core structure for support purposes.

The brush C is preferably formed by helically winding a single brush strip 10 so that its adjacent convolutions may be connected together in the manner previously described. In forming a cylindrical brush by interconnecting adjacent helical convolutions of a single brush strip, the said cylindrical brush is provided with a longitudinally extending offset 36 at one end thereof and a longitudinally extending offset 38 at the other end thereof. The offset 36 is defined by one end of the brush strip 10 and the offset 38 is defined by the other end of the brush strip 10, the said ends or offsets facing in opposite circumferential directions.

The cylindrical brush C may find a wide variety of independent applications, but it is particularly adapted to be used in forming a composite cylindrical brush strip structure when connected with one or more similarly formed independent cylindrical brushes. More specifically, the brush C may be connected in end-to-end relationship with a similarly formed cylindrical brush with the end of the brush having an offset 36 engaged with the opposite end of the said similarly formed brush. When so engaged, the oppositely facing offsets 36 and 38 on the similar brushes will abut each other in driving engagement so that one cylindrical brush can drive the other cylindrical brush of the composite brush structure. It will be seen that the engaged ends of the similar brushes can be secured together similarly to adjacent convolutions in a single cylindrical brush. That is, the forwardly offset wing 28 in the end convolution of the one brush will overlap or embrace the rearwardly offset wing in the end convolution of the other brush and the said wings can be welded together if desired. However, it may be more desirable to have the cylindrical brushes detachably connected in the composite brush structure so as to preserve their separate utility. When the brushes are arranged for detachable connection and independent utility, it is desirable that the ends of the strip making up a cylindrical brush, such as the brush C, be closed so that the fibers from the layer 32 cannot escape through the open ends of the channel member 12. This can be accomplished, as indicated by the reference numeral 40 in Fig. 3, by bend-

ing the end edges of the side walls 16 and 18 towards each other to close the ends of the channel defined between the said side walls 16 and 18 and the rear wall 14.

The method used in forming a cylindrical brush C may be described as comprising the step of providing a length of brush strip which includes a channel member having a rear wall and two side walls and also having two oppositely and generally laterally projecting flanges integral with the side walls and wherein the said brush strip also has a layer of brush fibers secured within the channel and projecting forwardly therefrom; and the further step of winding the brush strip to provide successive similar helical convolutions wherein the rear wall of the channel member faces inwardly and the fibers project outwardly and wherein the flange at one side of each brush strip convolution engages and is secured to the flange at the opposite side of the next adjacent convolution. In practising the foregoing method, the brush strip 10 may be helically wound upon a cylindrical rotating arbor or shaft and the overlapped wings 24 and 28 welded together while the said strip is wound upon the said arbor or shaft. Then, the forming arbor may be removed from the coiled strip.

While the novel brush strip has been described in connection with a method of forming a cylindrical brush wherein the interengaged channel convolutions provide the entire brush support structure in the form of a core, it should be understood that cylindrical brushes formed in accordance with this invention may also be used in brush structures wherein additional support structure is provided. That is, the cylindrical brush C can be mounted on an additional core structure if desired. However, it is an important aspect of the present invention that the interconnected convolutions of the strip provide all of the support structure necessary for most brush uses and installations.

The invention claimed is:

1. A brush strip comprising an elongated channel member having a rear wall and two side walls defining an open front longitudinally extending channel and which also has two oppositely projecting substantially co-planar lateral flanges formed integrally with the side walls and terminating in longitudinal edges, one of the said flanges being offset forwardly adjacent its longitudinal edge and the said flanges being constructed and arranged so that the forwardly offset portion of the said one flange will engage and overlap the other flange of a similar channel member when arranged in side-by-side relationship therewith and with the rear wall of the said channel member in substantially the same plane as the rear wall of the similar channel member, and a layer of brush fibers secured within the channel and projecting generally forwardly through the open front thereof.
2. A brush strip comprising an elongated channel member having a rear wall and two side walls defining an open front longitudinally extending channel and which also has two oppositely projecting substantially co-planar lateral flanges formed integrally with the side walls and terminating in longitudinal edges, one of the said flanges being offset forwardly adjacent its longitudinal edge and the other of the said flanges being offset rearwardly adjacent its longitudinal edge, the forwardly offset portion of the said one flange being constructed and arranged to overlap the rearwardly offset portion of the other flange of a similar channel member when arranged in side-by-side relationship therewith and with the rear wall of the said channel member in substantially the same plane as the rear wall of the similar channel member, and a layer of brush fibers secured within the channel and projecting generally forwardly through the open front thereof.
3. A cylindrical brush comprising a plurality of similar brush strip convolutions having a common center line and wherein the brush strip of each convolution comprises a channel member having an inner wall and two

side walls defining a generally U-shaped channel and also having two oppositely and generally laterally projecting substantially co-planar flanges integral with the said side walls and wherein the brush strip of each convolution also comprises a layer of brush fibers secured within the channel thereof and projecting generally outwardly therefrom, the flange at one side of each brush strip convolution having an offset portion adjacent its longitudinal edge which overlies and is rigidly secured to the flange at the opposite side of the next adjacent brush strip convolution with the inner wall of the channel member in each convolution being spaced from the center line a distance substantially equal to the spacing of the inner wall of the channel member from the center line in the next adjacent convolution.

4. A cylindrical brush comprising a plurality of brush strip convolutions having a common center line and wherein the brush strip of each convolution comprises a channel member having an inner wall and two side walls defining a generally U-shaped channel and also having two oppositely and generally laterally projecting substantially co-planar flanges integral with the said side walls and wherein the brush strip of each convolution also comprises a layer of brush fibers secured within the channel thereof and projecting generally outwardly therefrom, the flange at one side of each brush strip convolution having an outwardly projecting offset adjacent and along its longitudinal edge and the flange at the other side of each brush strip convolution having an inwardly projecting offset adjacent and along its longitudinal edge, the outwardly projecting offset of each brush strip convolution overlying and being rigidly secured to the inwardly projecting offset of the next adjacent brush strip convolution with the inner wall of the channel member in each convolution being spaced from the center line a distance substantially equal to the spacing of the inner wall of the channel member from the center line in the next adjacent convolution.

5. A cylindrical brush comprising a helically coiled brush strip having a channel member which includes an inner wall and two side walls defining a generally U-shaped channel and which also includes two oppositely and generally laterally projecting substantially co-planar flanges integral with the said side walls, one of the said flanges having an outwardly projecting offset which is constructed and arranged so that the said offset in one convolution of the strip embraces and is rigidly connected with the other flange in the next adjacent convolution of the strip, and a layer of brush fibers secured within the channel and projecting generally outwardly therefrom.

6. A cylindrical brush comprising a helically coiled brush strip having a channel member which includes an inner wall and two side walls defining a generally U-shaped channel and which also includes two oppositely and generally laterally projecting substantially co-planar flanges integral with the said side walls, one of the said

flanges having an outwardly projecting offset and the other of the said flanges having an inwardly projecting offset which outwardly and inwardly projecting offsets are constructed and arranged so that the outwardly projecting offset in one convolution of the strip embraces and is rigidly connected with the inwardly projecting offset in the next adjacent convolution of the strip, and a layer of brush fibers secured within the channel and projecting generally outwardly therefrom.

- 10 7. A cylindrical brush comprising a helically coiled brush strip having a channel member which includes an inner wall and two forwardly converging side walls defining a channel having a narrow neck and which also includes two substantially co-planar flanges projecting in 15 opposite generally lateral directions from the outer edges of the said side walls and which are formed integrally with the said side walls, one of the said flanges having an offset which projects outwardly and the other of said flanges having a substantially equal offset which projects inwardly, the said offsets being constructed and arranged so that the outwardly projecting offset in one convolution of the strip embraces and is rigidly connected with the inwardly projecting offset in the next adjacent convolution of the strip, a core wire located at least partly within 20 the channel and extending therealong, and a layer of brush fibers folded around the core wire within the channel and engaged by the said side walls and having end portions projecting outwardly through the neck of the channel.
8. A cylindrical brush comprising a helically coiled 25 brush strip with the first convolution of the strip providing one end of the cylindrical brush which one end has a longitudinally extending offset defined by one end of the strip which faces in one circumferential direction and with the last convolution of the strip providing the 30 other end of the cylindrical brush which other end has a longitudinally extending offset defined by the other end of the brush strip which faces in the opposite circumferential direction, the said strip including a channel member having an inner wall and two side walls defining 35 a generally U-shaped channel, the said channel member also having oppositely and generally laterally projecting substantially co-planar flanges integral with the said side walls which flanges are constructed and arranged so that the flange at one side of the channel member in one convolution of the strip embraces and is rigidly connected 40 with the flange at the other side of the channel member in the next adjacent convolution, and a layer of brush fibers secured within the channel and projecting generally outwardly therefrom.
